CLOTHESLINE FASTENING DEVICE

Ethel P. Ashcroft, Colorado Springs, Colo., assignor of one-eighth to Henry T. McGarry, one-fortieth to Ruth M. Burns, and one-fourth to Lucile Dee Latting, all of Colorado Springs, Colo.

Application June 3, 1938, Serial No. 211,646

1 Claim. (Cl. 24—137)

My invention relates to fastening devices and more particularly to clothes line fastening devices.

One of the principal objects of my invention is to provide a clothes line fastening device that is simple in construction, efficient in operation, reliable in use and economical in manufacture.

Another object of my invention is to provide a device of the above described character equipped with means for facilitating the attachment thereof to articles suspended from a clothes line whereby said articles are reliably secured to said line.

Other objects and advantages will be apparent from the following description, appended claim and annexed drawing.

Referring to the drawing wherein like reference characters designate like parts throughout the several views:

Figure 1 is a front elevation of my invention having a section thereof broken away to show the article engaging face of the ball or spherical-like member.

Figure 2 is a side elevation thereof illustrating the same clamped to an article suspended from a clothes line.

Figure 3 is a view similar to Figure 2 illustrating the position of the parts when about to be moved to article clamping position.

Figure 4 is a sectional view taken on the line 4—4 of Figure 1.

In practicing my invention there is illustrated a clothes line 5 having suspended therefrom the folded sides of an article 6, for instance clothing or the like. Securing said article to said line is my novel form of fastening device 7 comprising a length of wire coiled between the ends thereof as at 8 to form a pair of resilient arms 9 and 10. The free end of the arm 9 is fashioned with a resilient looped section 11 secured within a circumferentially extending groove 12 of a ball or spherical-like member 13. The arm 10 is fashioned between the ends thereof with a flattened section 14 of arcuate configuration in side elevation and at the free end thereof with a finger loop 15.

The member 13 is formed with a segmented article engaging face 16 adjacent the section 14 of the arm 10 and said face is of a like contour as the inner opposed face of the section 14 whereby, when the face 16 and the section 14 engage the folded sides of an article suspended from the line 5, said article will be clamped between said face 16 and said section 14 in appressed condition over said face as clearly illustrated in Figure 2 of the drawing.

When it is desired to secure the article 6 to the line 5, the ball-like member 13 is positioned above the line 5 in a manner whereby the line and article engage within the crotch between the member 13 and section 14 as clearly illustrated in Figure 3.

In this position, pull is exerted through the medium of the finger loop 15 and the fastening device drawn downwardly about the sides of the article. As the fastening device is drawn downwardly, the resiliency of the arms 9 and 10 permit the arm to spread and dispose the line 5 in a plane above the axis of the member 13 as clearly illustrated in Figure 2. The curved face of the member 13 coacts with the line and article to effect the spreading of the arms 9 and 10. In this position the device is securely clamped to the article and line.

What I claim is:

In a fastening device, a length of wire coiled between the ends thereof to form a pair of resilient arms, one of said arms formed with a flattened section between the ends thereof and terminating in a finger-piece at the free end thereof, the other of said arms fashioned with a resilient loop at the free end thereof, a ball-like member fashioned with a circumferentially extending recess receiving said loop and provided with a segmented face having a contour corresponding to the contour of said flattened section and cooperating with said flattened section to clamp therebetween the folded sides of an article interposed between said arms and suspended from a line extending between said arms.

ETHEL P. ASHCROFT.
